UNITED STATES PATENT OFFICE.

THOMAS B. COUGHLAN, OF DETROIT, MICHIGAN, ASSIGNOR TO CHAMBERLAIN METAL WEATHER STRIP COMPANY, OF DETROIT, MICHIGAN, A CORPORATION OF MICHIGAN.

WEATHER-STRIP.

1,114,864.

Specification of Letters Patent. Patented Oct. 27, 1914.

Application filed November 16, 1911. Serial No. 660,642.

To all whom it may concern:

Be it known that I, THOMAS B. COUGHLAN, a citizen of the United States, residing at Detroit, in the county of Wayne and State 5 of Michigan, have invented certain new and useful Improvements in Weather-Strips, of which the following is a specification, reference being had therein to the accompanying drawing.

10 This invention relates to improvements in weather strips and more particularly to metallic weather strips, it being the primary object of the invention to provide an improved strip of the character mentioned 15 adapted to form a tight and binding engagement between a sliding sash and its frame when the sash is closed, thereby in a more efficient manner providing against rattling and forming an air and water tight joint 20 from end to end of the sash, and at the same time to provide a strip that will relieve the sash of the usual friction or binding tendency incident to the opening thereof.

To the above end, the invention embraces 25 a metallic sealing strip adapted to be positioned upon, and connected as desired, to the usual frame of the window and a coöperating metallic strip or lining to be positioned upon and connected as desired to the adjacent wall of the window sash, one of the said 30 strips having a rib projecting at an angle to the body thereof and tapering from end to end and the other strip a coöperating receiving 35 groove or recess substantially similarly tapered whereby when the sash is moved to closing position the rib will become wedged in the recess formed by the side walls of the groove, and whereby when the sash is opened the same will be freed from frictional holding 40 engagement, the groove constituting a loose guide for the rib in said opening operation.

For the purpose of convenience that portion of the construction forming the receiving groove or recess for the ribbed strip will 45 be described and illustrated as applied to the sash, and the ribbed strip as applied to the frame for the sash though it is to be understood that these parts may be reversely arranged, and it is contemplated by the invention to provide a strip of the character 50 stated which may be readily applied to windows of ordinary construction without the necessity of resorting to special tools and to this end the sash may be provided with a 55 groove straight from top to bottom in which

the metallic tapered groove of the strip is suitably positioned and held in place.

Further the invention embraces means whereby the walls of the receiving groove may give relative to the rib of the strip to accommodate itself to variations in the line of the latter, or vice versa, together with means whereby the strip will operate effectively at all times for the purposes recited regardless of the swelling and contraction of the frame 60 or sash incident to weather conditions.

Other improvements and novelty details in the construction and arrangement of the parts will be more particularly referred to hereinafter in the description to follow and 70 for a clear understanding of the invention reference is directed to the accompanying drawings forming a part hereof, and wherein is disclosed for the purpose of illustration convenient and satisfactory embodiments of 75 the invention.

In the drawings: Figure 1 is an elevation of a window frame cut away with the sealing strip applied thereto, Fig. 2 is a perspective view of the strip detached, Fig. 3 is a horizontal section illustrating the sash in position in the groove in the frame and in partially opened position, with the strip in place, Fig. 4 is a horizontal similar view, the sash being in closed position, and the members of the strip being wedged or in binding 80 relation, Fig. 5 is an enlarged detailed view of the lining strips, and Fig. 6 is a slightly modified form of the lining strip constituting the receiving groove for the sealing 85 strip.

With more particular reference to the drawings, wherein like reference characters refer to corresponding parts throughout the several views 1 is a window frame of ordinary construction having the usual sash, groove or guideway 2.

3 is a sealing strip the same being preferably formed of metal and having a relatively wide base or body part 3^a adapted to 100 rest upon the base of the sash groove and to be secured if desired in any convenient manner as by tacks 3^b. Arranged conveniently adjacent one edge of said strip is a sealing rib 3^c, the same being conveniently formed by striking up the metal and extending from top to bottom of the strip and tapering to a relatively wide base portion. The said rib conveniently connects with a relatively short offset part 3^d constituting in effect a 105 110

continuation of the base 3^a, but preferably free from connection with the frame, whereby to permit the rib to accommodate itself to the receiving groove of the coöperating strip.

The sash 4 may be of ordinary construction but is preferably provided with a wooden body part to which the grooved strip is applied. This grooved strip may 10 and preferably does constitute a part of a metallic casing 5 for said wooden body part. The said casing overlies the opposite surfaces of the sash and extends to the edge thereof as shown. The edge of said 15 sash is provided with a groove 4^a which extends from top to bottom thereof, and to avoid the necessity of providing special tools for the formation of a groove tapering from top to bottom, the said groove is 20 preferably straight throughout and may be easily formed. The casing 5 conveniently has an edge extension 5^a overlying the edge of the sash and is struck up or otherwise provided with a groove 5^b, which 25 said groove tapers from top to bottom, in accordance with the taper of the rib 3^c, the said groove 5^b being smaller however than the receiving groove 4^a of the sash, as more clearly illustrated in Figs. 3 and 4, whereby 30 to provide for the swelling and contraction of the sash, without destroying the taper of the groove 5^b and preventing the side walls of the groove 5^b from being forced inwardly and interfere with the ready operation of 35 the sash. The casing 5 is conveniently severed at 5^c thereby providing a rib which is yieldable throughout its length to accommodate itself to the rib of the strip on the frame, and conveniently the rib 5^b which 40 forms the receiving groove is slightly smaller in width than the rib 3^c, so that when the sealing rib of the frame engages the lining groove of the sash when the sash is closed, the flanges of the lining will be expanded somewhat to create a metallic binding engagement between the flanges of the 45 lining and the sides of the receiving flange. Also the sealing rib is of a depth slightly in excess to that of the receiving groove 50 whereby in the opening movement of the sash there will be but a line point of contact between the sash and frame, namely at the point of engagement between the base of the rib 3^c and the base of the groove 5^b. 55 If desired a sash of ordinary construction may be provided having a receiving groove substantially straight from top to bottom thereof, and the metallic lining for the groove may be formed in various ways, it 60 being desired however to provide a lining so arranged in the groove as to permit of swelling and the like without interfering with the operation of said lining, and to per-

mit of one or more of the side walls to give. As an illustration I have shown in the 65 slightly modified construction of Fig. 6 a substantially U-shaped metallic lining 6 tapering from top to bottom and adapted to be secured as by nails 6^a passing through the base of the U-shaped member leaving 70 the opposite arms 6^b of said strip free from engagement whereby they may readily give to accommodate the groove to the sealing strip.

The construction being as described the 75 operation is obvious. When the sash is lowered into closed position the sealing rib will be wedged into binding engagement with the walls of the receiving groove 5^b thereby providing against rattling of the 80 sash and forming an air tight joint between the sash and frame. In the opening movement of the sash the same is relieved of any friction incident to the strip, and the relatively narrow line point of contact 85 between the sealing strip rib and the base of the lining will assist in the opening operation.

What I claim is:

The combination with a window frame 90 and a sash, one of the parts being provided with a vertical groove substantially rectangular shape in cross section and of uniform cross sectional area, of a weather strip including two flat metallic strips fitted against and secured to the window frame and the sash respectively so as to slide on each other in the raising and lowering of the sash, one of the strips being bent intermediate of its side edges to form a longitudinal groove, the bent portion fitting in the said groove and being approximately rectangular shape in cross section to line the same and tapered longitudinally so as to diverge from the walls of the said first mentioned groove and thereby allow for a yielding of the lining thereof, and the other strip being bent intermediate of its side edges to provide a hollow longitudinal rib substantially rectangular in cross section and slideable in and guided by the groove of the first mentioned strip and tapered longitudinally to wedge therein when the sash is at the limit of its movement in one direction, said strips being attached to the sash and to the 100 window frame at one side of the said bent portions and being free at the opposite sides to permit a yielding of the rib and groove of the said strips.

In testimony whereof I affix my signature 120 in presence of two witnesses.

THOMAS B. COUGHLAN.
